DESIGN FOR A COMBINED RADIO, CLOCK, AND TABLE LAMP

William J. Henken, Sioux City, Iowa

Application April 26, 1941, Serial No. 100,632

Term of patent 14 years

To all whom it may concern:

Be it known that I, William J. Henken, a citizen of the United States residing at Sioux City, in the county of Woodbury and State of Iowa, have invented a certain new, original, and ornamental Design for a Combined Radio, Clock, and Table Lamp, of which the following is a specification, reference being had to the accompanying drawing, forming a part thereof, in which:

Figure 1 is a front elevation of the combined radio, clock, and table lamp showing my new design,

Figure 2 is a side elevation of the same, and
Figure 3 is a plan view.

I claim:

The ornamental design for a combined radio,
clock, and table lamp, as shown.

WILLIAM J. HENKEN.
